(57) **CLAIM**

The ornamental design for a frame for a truck cap door as shown and described.

DESCRIPTION

FIG. 1 is a front side perspective view of a frame for a truck cap door showing our new design;

FIG. 2 is a rear side perspective view thereof;

FIG. 3 is a front view thereof;

FIG. 4 is a rear view thereof;

FIG. 5 is a bottom plan view thereof, the top plan view is the mirror image of the bottom plan view; and,

FIG. 6 is a left side view thereof, the right side view is the mirror image of the left side view.

The broken lines in the drawings are included to show portions of the frame for a truck cap door that form no part of the claimed design.
